UNITED STATES PATENT OFFICE.

AUGUST HORMEL, OF NEW YORK, N. Y.

ELECTRIC ANNUNCIATOR.

SPECIFICATION forming part of Letters Patent No. 444,245, dated January 6, 1891.

Application filed July 29, 1890. Serial No. 360,297. (No model.)

To all whom it may concern:

Be it known that I, AUGUST HORMEL, a citizen of the United States, and a resident of New York, in the county of New York and 5 State of New York, have invented certain new and useful Improvements in Electric Annunciators, of which the following is a specification.

My invention relates to an improved electric annunciator for hotels and dwelling-houses; and the invention consists of an annunciator having a pivoted elbow-lever, which, when the same is released from an armature by an electric current, drops and shows the 15 number-plate. By means of a lifting-lever the elbow-lever is then replaced in its former position. I attain these objects by the mechanism illustrated in the accompanying drawings, in which—

20 Figure 1 is a front view of my improved annunciator, and Fig. 2 is a side view of the same.

Similar letters of reference indicate corresponding parts.

A in the drawings represents a metallic C-shaped frame having outwardly-extending shanks A' and A², which is riveted or otherwise secured to the back wall of the annunciator-case. An electro-magnet B is attached to the upper shank A' of the frame A, and 25 to the under side of the lower shank A² an elbow-lever C is pivoted, which elbow-lever has an aperture c, and on its free end a clamp c' for holding the number-plate.

To the inside of the back part of the frame 30 A an armature-arm D is pivoted, which armature-arm has on its free end a knob or hook d. When the armature is in its normal position, the free end of the same projects through the aperture of the elbow-lever C and holds 35 the said lever in an upright position by means of the knob or hook d, the armature resting on the lower part of the border of the said aperture, and the knob or hook d engaging the outer rim of the said aperture, as clearly 40 shown in Fig. 1.

45 E is a lifting-lever of wire, having upwardly-bent arms e, which arms are hinged to the back wall of the annunciator-case. The end of one arm e projects through one of the side 50 walls of the annunciator-case and terminates in a crank-arm e². When the crank-arm is

turned upward, the lifting-lever is also moved in the same direction, so that the lower part e' of the lifting-lever strikes the elbow-lever C. The wire ends of the electro-magnet are 55 connected with an electric battery in such a manner that the electric current is closed by means of a suitable switch or push button, (not shown in the drawings,) as generally used in annunciators of this class.

60 My improved annunciator operates in the following manner: As soon as the electric circuit is closed by the push-button, as aforesaid, the core in the electro-magnet becomes magnetic and the armature D is attracted by 65 the core. The elbow-lever C is thereby released from the knob or hook d of the armature and drops into a horizontal position, as shown in Fig. 2, whereby the number-plate, fastened to the clamp on the free end of the 70 elbow-lever, is shown. The pivoted end of the elbow-lever is rounded off, so that the turning of the same on its pivot-pin is allowed. The elbow-lever C is so pivoted to the shank A² of the frame A that the exterior end c' of 75 the rounded-off portion of the elbow-lever abuts against the lower side of the said shank A², whereby the elbow-lever is kept in a horizontal position, as shown in Fig. 2. As soon as the electric circuit is broken, the armature 80 is released from the core of the electro-magnet and rests on the shank A². To bring the elbow-lever into its former position the crank-arm e² is turned upward and the lifting-lever strikes against the elbow-lever, so that the 85 latter is raised and the lower part of the border of the aperture c is pushed against the knob or hook of the armature. As soon as the aperture of the elbow-lever has passed the knob on the end of the armature the elbow-lever is caught by the said knob and kept in 90 an upright position, as the knob will abut against the outside of the lower border of the aperture in the elbow-lever, as shown in Fig. 1.

Having thus described my invention, I 95 claim as new and desire to secure by Letters Patent—

1. In an electric annunciator, the combination of a C-shaped frame, with an electro-magnet fastened to the upper shank, an armature pivoted to the back part, and an elbow-lever pivoted to the lower shank of said 100

frame, the armature having a knob or hook on its free end which engages the elbow-lever by means of an aperture when the latter is in upright position, substantially as set forth.

- 5 2. In an electric annunciator, the combination of an electro-magnet on the upper shank of a frame, and an armature pivoted to the back part of said frame and having a knob or hook on its free end, with an elbow-lever
10 having an aperture and being pivoted to the lower shank of said frame in such a way that the same is kept in upright position by the

knob or hook of the armature, and a lifting-lever by which the elbow-lever is lifted when the same is released from the armature and in 15 horizontal position, substantially as set forth.

Signed at New York, in the county of New York and State of New York, this 23d day of July, A. D. 1890.

AUGUST HORMEL.
